UNITED STATES PATENT OFFICE.

AXEL S. ELIASON, OF WHitestone, NEW YORK.

MARBLE SHOOTER.

Application filed October 5, 1925. Serial No. 60,384.

This invention relates to marble shooters, and has for its primary object to provide a device of this character for use in the playing of juvenile games with marbles whereby 5 the marble may be projected with the necessary force without contact of the hand with the ground or requiring that the player should assume a kneeling position.

More particularly, my invention has for 10 its primary object a device for the above purpose which may be easily operated from a stooping position to accurately project the marble, said device including means for supporting a plurality of marbles within a 15 magazine and for automatically releasing the marbles in succession so that they will assume the required position for their projection when the device is operated.

It is a further general object of the invention 20 to provide a device of the above character which is simple, as well as strong and durable in its construction and may be manufactured and sold at nominal cost.

With the above and other objects in view, 25 the invention consists in the improved marble shooter; and in the form, construction and relative arrangement of its several parts as will be hereinafter more fully described, illustrated in the accompanying drawings 30 and subsequently incorporated in the subjoined claims.

In the drawing, wherein I have illustrated one simple and practical embodiment 35 of the device, and in which similar reference characters designate corresponding parts throughout the several views.

Figure 1 is a perspective view illustrating 40 the manner of use of my improved marble shooter;

Fig. 2 is an enlarged front elevation of 45 the device, partly broken away;

Fig. 3 is a longitudinal sectional view taken on the line 3-3 of Fig. 2, and

Figs. 4 and 5 are horizontal sectional 50 views taken substantially on the lines 4-4 and 5-5 respectively, of Fig. 3.

Referring in detail to the drawing, for 55 purposes of illustration, I have shown the magazine or container adapted to receive and support a plurality of marbles M in vertically superimposed relation to each other as consisting of a cylindrical tube 5 of sheet metal having a suitable operating handle 6 fitted into the upper end thereof. The lower end of this tubular magazine is 60 provided with a horizontally disposed bifur-

cated base 7. The front side of said magazine has a longitudinally extending slot 8 therein, the wall of said tube at its lower end and at each side of said slot being cut 60 away to provide an opening indicated at 9 through which the marbles are projected in a manner to be hereinafter described. To the outer side of the tube 5 adjacent each edge of the slot 8 therein the resilient wires 65 or other equivalent elements 10 are suitably fixed at their upper ends, the lower free end portions of these resilient wires extending downwardly over the opening 9 to a point adjacent the base plate 7. The distance between the free ends of the wires 10 is appreciably less than the diameter of the marble M so that when the marble occupies a position in the lower end of the magazine opposite the opening 9 the marble will be retained in such position by the wires 10 until it is forcibly projected through said opening.

The wall of the magazine 5 at its rear side is provided with a horizontally projecting lug 11, preferably struck outwardly 80 from said wall to which the angular upper end 13 of a resilient projecting member 12 is suitably fixed. As herein shown, this member is in the form of a length of wire and at its other lower end is provided with a relatively long horizontally disposed portion 14 which extends through an opening 15 in the rear side of the wall of the tube 5 and normally supports the series of marbles M in the magazine in the manner illustrated 85 in Fig. 3 of the drawings.

Above the opening 15, the wall of the magazine is also provided with a second outwardly struck lug 16, the end of which is reduced as at 17 and extends through a 90 longitudinal slot 19 in a vertically positioned channel-shaped plate 18. Adjacent its upper end said plate is provided with a second slot 20 to receive the similarly reduced end of the lug 11, thus it will be understood that 95 these lugs 11 and 16 retain the plate 18 in spaced parallel relation to the tubular magazine and guide said plate in its movement relative thereto. At its lower end the plate 18 is formed with a horizontally or laterally 100 extending foot 21 adapted for engagement with the ground.

In a suitable bearing 22 on the plate 18 a trip rod 23 has its intermediate portion pivotally mounted. One end of this rod 110 indicated at 24 extends downwardly and normally bears against the plate 18 while

the other end of said rod projects laterally and terminates in an angularly bent portion 25. This end of said rod is adapted to be engaged by an inwardly extending cam projection 26 formed in the vertical length of the wire member 12 intermediate the ends thereof.

In the operation of the marble shooter, the player assumes a stooping position substantially as shown in Fig. 1, and with the foot 21 of the plate 18 bearing on the ground, exerts a downward pressure on the handle 6. The magazine and the projecting member 12 will thus move downwardly as a unit relative to the plate 18 and the inclined or cam portion 26 of the member 12 riding upon the angular end 25 of the trip member 23 causes the lower angular end of said member to be withdrawn from beneath the marbles in the magazine so that the lower marble falls down and rests upon the base plate 7. This position of the parts is substantially that shown in dotted lines in Fig. 3 of the drawings, and it will be obvious that when the member 12 is thus sprung laterally it is placed under considerable tension so that when the cam part 26 of said member moves below the end 25 of the trip 23, said member immediately returns to its normal position and the lower end 14 thereof passing inwardly through the opening 15 in the wall of the magazine, strikes the lower marble M and forcibly projects the same through the opening 9 towards the objective. In this projection of the marble, the lower ends of the wires 10 readily yield or spring apart so that they offer no appreciable resistance to the projecting force. When the player lifts the handle 6 with the magazine and the projecting member 12 relative to the plate 18, the inwardly projecting bend or cam part in the wire member 12 lifts the laterally projecting end of the trip member 23 upwardly until said projection is again disposed above the trip member when the latter returns to its normal position limited by contact of the end 24 of said trip member against the plate 18.

From the foregoing description considered in connection with the accompanying drawings, the construction and manner of operation of my improved marble shooter will be clearly and fully understood. It will be seen that I have produced a device which may be expeditiously operated with a high degree of accuracy and which eliminates the necessity of the player kneeling or placing his hand containing the marble upon the ground. Also by reason of the fact that a comparatively large number of the marbles may be contained in the magazine, the marbles may be expelled or projected therefrom in rapid succession. The handle 6 may be readily removed or detached from the upper end of the magazine for the purpose of re-

loading the latter. In view of the relatively simple form and construction of the several parts of the device, it will likewise be appreciated that such an article may be manufactured economically and retailed at a relatively low price. 70

I have herein described an embodiment of my improved marble shooter which I believe to be entirely practical, but it will nevertheless, be understood that the device is susceptible of many minor modifications in the form, construction and relative arrangement of its several parts, and I therefore, reserve the privilege or resorting to all such legitimate changes as may be fairly embodied within the spirit and scope of the invention as claimed. 75 80

I claim:

1. A marble shooter comprising a magazine for the marbles having an opening at its lower end through which the marbles are adapted to be projected, means yieldingly resisting movement of the marbles through said opening, a movable projecting member mounted on the magazine and having a part normally disposed beneath the series of marbles to support the same in superposed relation therein, a plate having a foot portion adapted for engagement with the ground, guide means on said magazine movably engaged by said plate, and a trip member mounted on said plate to coat with the projecting member when the magazine and the projecting member are moved downwardly relative to the plate to cause a marble to be projected from the lower end of the magazine. 90 95 100

2. A marble shooter comprising a magazine for the marbles having an opening at its lower end through which the marbles are adapted to be projected, means yieldingly resisting movement of the marbles through said opening, a movable projecting member mounted on the magazine and having a part normally disposed beneath the series of marbles to support the same in superposed relation therein, a plate having a foot portion adapted for engagement with the ground, guide means on said magazine movably engaged by said plate, a trip member pivotally mounted upon said plate and having a part coacting therewith to limit the pivotal movement of said member to its normal position, and said projecting member having a cam part engaging the trip member in the downward movement of the magazine relative to said plate whereby said projecting member is actuated to permit downward movement of the marbles in the magazine and to project the lowermost marble 110 115 120 125 from the opening in the wall of said magazine.

3. A marble shooter comprising a marble magazine having an opening in its wall through which the marbles are adapted to 130

be projected, a ground engaging plate, said plate and the magazine having coacting means guiding the movement of said magazine relative to said plate, a resilient projecting member fixed at one of its ends to the magazine and movable therewith, and trip means on said plate adapted to cooperate with said member to actuate the latter and cause the other end thereof to forcibly engage and project the lowermost marble from the magazine.

4. A marble shooter comprising a marble magazine having an opening at its lower end through which the marbles are adapted to be successively projected, a ground engaging plate, said magazine having parts connected with said plate by which said magazine is guided for relative movement, a resilient wire having a fixed connection at one of its ends with said magazine, the other end of said wire normally extending through an opening in the magazine wall to support the series of marbles therein, and said wire intermediate of its ends having a cam loop formed therein, and a trip member mounted on said plate adapted to be engaged by said cam loop in the downward movement of the magazine whereby the lower end of said projecting member is withdrawn to permit the marbles to drop downwardly in the magazine, and said projecting member then released whereby the lowermost marble will be forcibly projected from the magazine.

5. A marble shooter comprising a marble magazine having an opening at its lower end through which the marbles are adapted to be successively projected, a ground engaging plate, said magazine having parts connected with said plate by which said magazine is guided for relative movement, a resilient wire having a fixed connection at one of its ends with said magazine, the other

end of said wire normally extending through an opening in the magazine wall to support the series of marbles therein, and said wire intermediate of its ends having a cam loop formed therein, an angular trip rod pivotally mounted upon said plate and having one of its ends normally bearing against said plate to prevent pivotal movement of said rod in one direction whereby the other end of said trip rod coacts with the cam portion of the wire projecting member in the downward movement of the magazine to withdraw the free end of said member from the magazine and permit the marbles to move downwardly therein and then release said projecting member to forcibly project the lowermost marble from the magazine, said pivoted trip rod being pivotally moved from its normal position by the cam portion of the projecting member in the upward movement of the latter with the magazine relative to said plate.

6. A marble shooter comprising a ground engaging support, a marble magazine mounted upon the support for movement relative thereto, and means automatically operated upon movement of said magazine in one direction relative to the support to project a marble laterally from one end of the magazine.

7. A marble shooter comprising a support, a marble magazine mounted upon the support for movement relative thereto, a marble projecting member mounted upon the magazine and movable therewith, and means on the support coacting with said member when the magazine is moved in one direction relative to the support to actuate said member and project a marble from the magazine.

In testimony that I claim the foregoing as my invention, I have signed my name hereto.

AXEL S. ELIASON.
